US0D1112199S

(12) **United States Design Patent** (10) **Patent No.:** **US D1,112,199 S**
(45) **Date of Patent:** **** Feb. 10, 2026**

(54) **INTELLIGENT ACCESS CONTROL DEVICE**

(71) Applicants: **THALES DIS FRANCE SA**, Meudon (FR); **10 SQUARED LTD**, York (GB)

(72) Inventors: **Ivan Minaya**, Meudon (FR); **Yann Tremeac**, Meudon (FR); **Françoise Bergasse**, Meudon (FR); **Pierre Luc Arnaud**, Meudon (FR); **Gary Steele**, York (GB); **Pat Holbrough**, York (GB); **Tom Langford**, York (GB); **Matthew Baxter**, York (GB)

(73) Assignees: **THALES DIS FRANCE SAS**, Meudon (FR); **10 SQUARED LTD**, York (GB)

(**) Term: **15 Years**

(21) Appl. No.: **29/957,470**

(22) Filed: **Aug. 14, 2024**
